UNITED STATES PATENT OFFICE

2,328,594

ANTINEURITIC COMPOUND

Robert R. Williams, Roselle, and Joseph K. Cline, Woodbridge, N. J., assignors to Research Corporation, New York, N. Y., a corporation of New York

No Drawing. Application April 1, 1937,
Serial No. 134,334

36 Claims. (Cl. 260—251)

This invention relates to the production of antineuritic compounds and, particularly, to the synthesis of vitamin B₁, salts thereof, and related products having the essential physiological properties of vitamin B₁. This application is a continuation in part of our copending applications Serial No. 85,350, filed June 15, 1936, and Serial No. 94,430, filed August 5, 1936.

The isolation and structure of vitamin B₁ are referred to in the following articles: Jr. Am. Chem. Soc., vol. 57, pp. 229, 517, 536, 1093, 1751, 1849 and 1887 (1935); vol. 58, pp. 1063, 1504 and 1803 (1936); vol. 59, p. 216 (1937).

The present invention relates to methods by which vitamin B₁ and kindred compounds may be synthesized. These syntheses make available vital substances which may be incorporated in pharmaceutical products and in foods deficient in vitamin B₁.

An object of the invention is to provide synthetic vitamin B₁, its salts and related compounds having the essential physiological properties thereof.

Another object of the invention is to provide effective and reliable processes for the production of vitamin B₁, its salts, and related compounds having similar physiological reactions.

Vitamin B₁ is obtained from natural sources in the form of its acid salts, usually as the chloride hydrochloride. These salts have the following general structure:

in which X is an anion and HX¹ is an acid, the anion portion of which may or may not be the same as the one represented by X.

The syntheses embodying this invention comprise the coupling of two distinct radicals or groups to form the vitamin or other closely allied substances. One of these groups is a derivative of pyrimidine having the constitution indicated by the following formula:

This has been termed the pyrimethyl group and the atoms of the pyrimidine ring portion thereof

have been numbered as shown in the structural formula given hereinabove to designate the positions of any attached groups or elements. It is to be understood that when the term "pyrimethyl" is used herein or in the annexed claims to define a compound, it means that the group or element following this term is attached to the CH₂- group located in the 5-position on the pyrimidine ring portion of the compound. It will be observed that in vitamin B₁, the methyl group and the amino group are attached to the pyrimethyl group in the 2 and 6 positions, respectively, and that hydrogen is in the 4 position.

The other radical entering into the coupling reaction is a substituted thiazole nucleus, the nucleus having the structure indicated by the following formula:

From an examination of the formula given hereinabove for the acid salts of vitamin B₁, it is evident that the thiazole nucleus contained in the natural vitamin has attached thereto a hydrogen atom in the 2 position, a methyl group in the 4 position and a β -hydroxy-ethyl group in the 5 position. The basic compound having these attached groups is described in Patent No. 2,134,015, granted October 25, 1938, to R. R. Williams, for Thiazole compounds. Acids add directly to this thiazole to form salts thereof and these salts may be used in the syntheses instead of the base, if desired.

For the sake of clarity the following description will, in general, be confined to the utilization of 2-methyl-6-amino-pyrimethyl compounds and 4-methyl-5- β -hydroxy-ethyl thiazole in the various coupling reactions embodying the invention, although it is to be understood that the invention is not limited to these particular pyrimethyl and thiazole derivatives.

It has been found that one of the instrumentalities by which the pyrimethyl radical can be coupled to a thiazole group is a salt of a pyrimethyl ester, such as 2-methyl-6-amino-pyrimethyl-bromide hydrobromide, which has the formula:

Acid salts of pyrimethyl esters of this general type may be coupled with a thiazole nucleus according to the following reaction:

In these equations X represents an acid radical and HX' is an acid. In the reaction which occurs, it will be observed that the pyrimethyl portion and the acid radical portion of the ester, represented by the symbol X , both unite with the nitrogen atom of the thiazole to produce a quaternary thiazolium compound.

It has been found that effective results may be obtained by first producing a mixed ether such, for example, as 2-methyl-6-amino-pyrimethyl-ethyl ether or 2-methyl-6-pyrimethyl-methyl ether and to obtain acid esters therefrom having the formula:

in which X is an acid radical or element in non-ionic combination and HX' is an acid, the anion portion of which may or may not be the same as the acid radical represented by X . The term "acid radical" as used herein is intended to denote not only a group of elements which act as a single element, e. g. the sulphate radical, but also elements, such as the halogens, which are acidic. The invention contemplates the reaction of a pyrimethyl ester of this type with a thiazole compound, such as 4-methyl-5- β -hydroxy-ethyl thiazole, or with a salt thereof, to produce a salt of vitamin B₁ or a closely related compound which has the essential physiological properties of vitamin B₁.

Among the pyrimethyl esters and acid salts thereof which may be employed in practicing the invention, there may be mentioned the bromide, acetate, lactate, benzoate, sulphate, phosphate, p-toluene sulphonate, benzene sulphonate and β -naphthalene sulphonate esters and acid salts thereof. A pyrimethyl ester of this type constitutes a means by which the pyrimethyl radical may be caused to unite with a thiazole nucleus, and a pyrimethyl ester may therefore be described as a reactive pyrimethyl compound, the term "reactive," as used herein, referring to the ability of the compound to react with a thiazole nucleus to produce a quaternary thiazolium derivative. It is further to be understood that the term "reactive pyrimethyl compound" means a compound having a reactive group attached to the methylene group in the 5-position on the pyrimidine ring portion thereof.

Substances known to have antineuritic potency have been found to have certain substituents in certain positions in the molecules making up the antineuritic substances. Thus, for example, antineuritic properties have been found in com-

pounds having a pyrimethyl group coupled with a thiazole group in which a methyl group is attached in the 2 position and an amino group in the 6 position with respect to the pyrimethyl portion of the compound and a methyl group is attached in the 4 position and a β -hydroxy-ethyl group in the 5 position of the thiazole portion of the compound.

However, instead of the 5- β -hydroxy-ethyl group, a functional derivative thereof may be employed. Thus, compounds having the general formula:

can be obtained, wherein X is an acid radical, HX' is an acid and Z is a functional derivative of an hydroxyl group (e. g. amino, halogen, acid radical, etc.). A "functional derivative" of a group, as that term is used herein, is a group or element that can readily be converted into or replaced by that group. The group or element represented by Z in this formula may be converted into an hydroxyl group after the formation of the compound represented by the formula. It is preferred, however, to employ a thiazole derivative having the hydroxy group already present therein in the proper position.

Instead of forming a pyrimethyl ester and separating it as a distinct compound a mixture of pyrimethyl alcohol or a pyrimethyl ether and an acid may be reacted directly with the appropriate thiazole, the important consideration being the use of a substance or a mixture which contains and will yield the pyrimethyl group in reactive condition. It is probable that such condensations of pyrimethyl alcohol, ether or amine with a thiazole in the presence of an acid proceed by the intermediate formation of a pyrimethyl ester of the acid. In carrying out the reaction, conditions should be chosen so as to supply an acid radical in order that the pyrimethyl radical and the acid radical may unite with the nitrogen atom of the thiazole compound to produce an antineuritic compound having the structure outlined above. The coupling reaction should preferably be carried out under acid conditions for the added reason that the antineuritic compounds produced are less stable under alkaline or neutral conditions. Also, because of the greater stability of their salts it has been found most advantageous to prepare and administer the antineuritic compounds in the form of their acid salts which have structures closely resembling that given hereinabove for the acid salts of vitamin B₁.

To illustrate the principles of the invention, specific examples will be given describing the coupling of 4-methyl-5- β -hydroxy-ethyl thiazole with the following 2-methyl-6-amino-pyrimethyl esters: bromide, acetate, lactate, benzoate, sulphate, phosphate, nitrate, benzene sulphonate, p-toluene sulphonate and β -naphthalene sulphonate.

This description will include a disclosure of a series of useful intermediate compounds containing the pyrimethyl radical from which the above esters may be prepared, one group comprising the ethers having the general formula:

wherein R^1 and R^2 are respectively alkyl or aralkyl radicals (methyl, ethyl, propyl, benzyl, etc.). By replacing the 6-oxy radical of this compound with a 6-amino radical and the $-OR^2$ group with an acid radical, e.g. the sulphate or a sulphonate or bromine, a compound is produced which is capable of coupling with a thiazole nucleus as above set forth.

In the above mentioned copending applications Serial No. 85,350 and Serial No. 94,430 a compound, designated therein as 2-methyl-5-ethoxy-methyl-6-oxy pyrimidine, and a method of preparing this compound were set forth. In accordance with one embodiment of the present invention, this compound is first produced and from it there is obtained an acid pyrimethyl ester which may be coupled with a suitable thiazole radical to produce antineuritic compounds. The description contained in these prior applications will be given herein for the sake of completeness. However, since the group

is designated the pyrimethyl group herein, changes in the nomenclature used in the previous specifications will be made wherever appropriate to utilize this terminology. For example, the compound termed 2-methyl-5-ethoxy-methyl-6-oxy pyrimidine in the former applications will be designated herein as 2-methyl-6-oxy-pyrimethyl-ethyl ether.

A description of the process for making 2-methyl-6-oxy-pyrimethyl-ethyl ether will first be given and this will be followed by specific examples of processes embodying the invention in which various pyrimethyl esters are obtained from this compound and are condensed or coupled with a thiazole compound to produce salts of vitamin B₁ and related compounds having the antineuritic properties thereof.

Example I

A suitable pyrimethyl ester for use in the coupling reaction is 2-methyl-6-amino-pyrimethyl bromide and one process for making this bromide ester comprises a series of steps including those set forth in the aforementioned copending applications which are substantially as follows:

1. β -Ethoxy-propionic-ethyl ester
2. Sodio-formyl- β -ethoxy-propionic-ethyl ester
3. 2-methyl-6-oxy-pyrimethyl-ethyl ether
4. 2-methyl-6-chlor-pyrimethyl-ethyl ether
5. 2-methyl-6-amino-pyrimethyl-ethyl ether
6. 2-methyl-6-amino-pyrimethyl-bromide
7. Coupling of hydrobromide of the bromide ester with a thiazole compound to form an antineuritic compound

The sequence and significance of these steps may be made more apparent by writing the structural formulae of the compounds, as follows:

The steps in the following detailed disclosure correspond to the numbers in the above schedule.

Step 1.—A mixture of 116 gms. of sulphuric acid (sp. g. 1.84), 18 gms. of water, 200 cc. absolute alcohol, and 99 gms. of β -ethoxy propionitrile is heated, under refluxing, for about six hours. At the end of this time, the mixture is cooled and allowed to stand until all the ammonium bisulphate produced has crystallized out. The ammonium bisulphate is filtered off, washed several times with absolute alcohol, and the combined filtrate and washings distilled to remove the major portion of alcohol. Ice water is added to the residue, the excess acid neutralized, and the solution finally made slightly basic by the addition of sodium carbonate. The mixture is then extracted with ether, the ethereal solution dried over sodium sulphate, and the solution fractionated by distillation. β -ethoxy propionic-ethyl-ester is obtained in the form of a pleasant smelling, water-white liquid having a boiling point of about 70-72° at 24 mm. pressure. In this reaction compounds having alkyl radicals (and aralkyl radicals) other than the ethyl radical can be substituted.

Step 2.—A mixture of 73 gms. of β -ethoxy-propionic-ethyl ester and about 40 gms. of ethyl formate is slowly dropped onto 12 gms. of sodium wire covered with anhydrous ether. Hydrogen is evolved, and a yellow salt precipitates out of the ether. If the reaction proceeds slowly, without causing ebullition of the ether, the amount of sodium specified is sufficient. However, if the reaction proceeds violently, increasing amounts of sodium up to a total of two equivalents may be necessary. For best results, the time for addition of the ester is about eight hours. The thus formed sodio-formyl derivative is used within isolation in the succeeding reaction. It must be protected from atmospheric moisture and should be used promptly, as it is not very stable.

Instead of the above described derivative, compounds having the general formula:

wherein R and R' are alkyl or aralkyl radicals and M is an alkali metal, may be produced from appropriate reagents, if desired, by a similar method and used in the succeeding step.

Step 3.—To the ether suspension of the sodio-

formyl derivative obtained in Step 2, 45 gms. of acetamidine hydrochloride, 100 cc. of absolute alcohol, and a solution of 12 gms. of sodium in 200 cc. of absolute alcohol are added. The ether is distilled off, and the mixture heated, under refluxing, for about sixteen hours. The contents of the flask are then cooled, neutralized with 10% acetic acid, and evaporated down on a steam bath. The residue is taken up in a small amount of water and extracted repeatedly with chloroform. The combined chloroform extracts are dried with sodium sulphate and the chloroform removed by evaporation. The remaining brown, gummy substance is treated with dioxane, after which a portion dissolves and a considerable quantity of the gum is solidified. The solid is dried and sublimed in high vacuo at 140° C. The sublimate is placed in a Soxhlet extractor and extracted repeatedly with anhydrous ether. The residue is dried and again sublimed in high vacuo, yielding substantially pure 2-methyl-6-oxy-pyrimethyl-ethyl ether having a melting point of about 175° to 176° C.

Instead of proceeding as above set forth the following preferred method of carrying out Step 3 may be employed:

To the reaction mixture obtained in Step 2, add carefully a mixture of 100 to 200 gms. of crushed ice and water, just sufficient to produce solution of the material. The ether separates and is removed. There is then added 45 gms. of acetamidine hydrochloride followed by 10 gms. of NaOH (in the form of a 30% NaOH solution). The mixture is allowed to stand 3 to 4 days, after which it is neutralized with strong hydrochloric acid and is then extracted repeatedly with chloroform. The chloroform solution is evaporated to dryness and the crude product, 2-methyl-6-oxy-pyrimethyl-ethyl ether, is dried to constant weight. For purification it can be crystallized from amyl ether.

Instead of the specific compound produced as above described, compounds having the general formula:

may be produced, wherein R¹ and R² are alkyl or aralkyl groups, by condensing compounds having the general formula indicated at the end of Step 2 with homologues of acetamidine, e. g. propamidine, butamidine, etc.

Step 4.—One gm. of 2-methyl-6-oxy-pyrimethyl-ethyl ether is heated with 8 cc. of phosphorous oxychloride for about three hours at 78° C. The phosphorous oxychloride is then removed in vacuo. The residue is poured onto ice and excess acid is neutralized by the addition of sodium bicarbonate or ammonia and the mixture extracted repeatedly with chloroform. The combined chloroform extracts are dried over sodium sulphate and the chloroform removed in vacuo. Approximately 1 gm. of an oily residue remains consisting largely of 2-methyl-6-chlor-pyrimethyl-ethyl ether.

By employing compounds having the general formula

wherein R¹ and R² are alkyl or aralkyl radicals, compounds having the general formula

are obtained.

Instead of the 6-chlor pyrimethyl compounds just described, the corresponding 6-brom and 6-iodo compounds, which may be made in an analogous manner, may also be used if desired.

Step 5.—The product of Step 4 is treated with about 5 to 15 cc. of alcoholic ammonia in a bomb tube at about 140° C. for a period of time sufficient to convert all bromine into ionic form e. g. three hours. The contents of the tube are then evaporated down, leaving a partly crystalline residue. This residue is dissolved in water, sodium bicarbonate or sodium carbonate is added and the solution extracted repeatedly with chloroform. The combined chloroform extracts are dried over sodium sulphate and the chloroform removed in vacuo, leaving an oily residue which crystallizes on standing and cooling. The crude product may be recrystallized from ether or ligroin, and pure 2-methyl-6-amino-pyrimethyl-ethyl ether, having a melting point of 89.5 to 90.5° C. is obtained. If desired, the crude product may be purified by repeatedly subliming it in high vacuo at 60 to 80° C.

By employing compounds having the general formula

compounds having the formula

may be obtained, wherein R¹ and R² are alkyl or aralkyl radicals.

Step 6.—The 2-methyl-6-amino-pyrimethyl-ethyl ether produced in accordance with the process outlined in Step 5 may be treated in various ways to produce a hydrobromide of 2-methyl-6-amino-pyrimethyl bromide. In one process 50 mgms. of 2-methyl-6-amino-pyrimethyl-ethyl ether are heated with 2 cc. of 60% hydrobromic acid in a bomb tube for about two and one-half hours at 100° C. The contents of the tube are then removed, and concentrated in vacuo.

When the solution reaches small volume, crystals will separate. One cc. of cold water is added and sodium bicarbonate is added to the clear solution. When the solution is neutral, a precipitate is formed. This precipitate is extracted with chloroform, the chloroform solution dried over anhydrous sodium sulphate and the chloroform finally removed in vacuo. The yield consists of about 20 mgms. of crystals which give a strongly positive test for bromine. At this stage, the crystals, consisting largely of 2-methyl-6-amino-pyrimethyl-bromide, are more or less contaminated with 2-methyl-6-oxy-pyrimethyl-bromide which may be removed as desired by extraction of the chloroform solution with dilute alkali.

About 20 mgms. of 2-methyl-6-amino-pyrimethyl-bromide are dissolved in 2 cc. of absolute alcohol and alcoholic hydrobromic acid is added whereupon a precipitate is formed. The alcohol

and excess hydrobromic acid are removed in vacuo, leaving an acid ester which is a 2-methyl-6-amino-pyrimethyl-bromide hydrobromide.

Step 7.—In one process of practicing the coupling reaction about five drops of synthetic 4-methyl-5- β -hydroxy-ethyl thiazole are added to the 2-methyl-6-amino-pyrimethyl-bromide hydrobromide residue produced in accordance with Step 6 and the mixture is heated at about 120-125° C. for several hours. The resulting dark, gummy reaction product when tested physiologically exhibits the characteristic antineuritic action of vitamin B₁.

Example II

In this example, the procedure outlined in Steps 1 to 5, inclusive, of Example I are followed to produce 2-methyl-6-amino-pyrimethyl-ethyl ether. This is then converted into a bromide hydrobromide as follows:

150 gms. of 2-methyl-6-amino-pyrimethyl-ethyl ether are heated with 7.75 liters of a 10% solution of hydrobromic acid in glacial acetic acid for two hours at 100° C. (This is a ratio of slightly more than 3 mols hydrobromic acid to one mole of the ether.) At the end of this time, the liquid remaining is decanted from the crystals which separate out. The crystals are washed several times with anhydrous ether and then may be purified by dissolving in a small amount of methanol and reprecipitating by the addition of the ether. The pure compound thus obtained melts at 192-103° C. and is a hydrobromide of 2-methyl-6-amino-pyrimethyl-bromide. The pure compound is not as stable as the crude product containing small amounts of free hydrobromic and glacial acetic acid, which appear to act as stabilizing agents.

Anal. calc. for C₆H₁₀N₂Br₂: C, 25.45; H, 3.21; N, 14.85; found, C, 26.56, 26.55, 26.48; H, 3.50, 3.62, 3.34; N, 14.71, 14.99.

The bromide hydrobromide produced in accordance with the preceding step is then coupled with a thiazole to produce an antineuritic substance in accordance with the following procedure:

150 gms. of the 2-methyl-6-amino-pyrimethyl-bromide hydrobromide, preferably in the crude stable form as obtained from the preceding step, are heated with 150 gms. of 4-methyl-5- β -hydroxy-ethyl-thiazole and 200 cc. of butanol for 15 minutes at 120° C. The pyrimethyl compound goes into solution and at the same time a precipitate settles out. The reaction mixture is diluted with 1 liter of boiling absolute ethyl alcohol and allowed to stand until no more material settles out. The alcoholic mother liquors are removed by filtration and the precipitate washed several times with small amounts of cold absolute ethyl alcohol. The product obtained melts at about 229° C. and consists of the crude bromide hydrobromide of the vitamin.

The precipitate then is recrystallized by dissolving in hot methanol, adding anhydrous ether to the hot solution until a permanent cloud appears and allowing to cool slowly. The condensation product thus obtained occurs as rosettes of needles which melt at 219-220° C. whereas the vitamin bromide hydrobromide from natural sources melts at 227-229° C.

With doses of 5 γ of either the crude or the recrystallized product, cures of polyneuritis are effected in rats on a vitamin B₁ free diet, which cures endure for about three days, indicating an activity equal to that of the bromide hydrobromide.

mide of the natural vitamin. Its absorption in the ultra violet is also identical with that of the corresponding salt of the vitamin from natural sources. The pure product appears to hold one-half mole of water of crystallization.

Anal. calc. for C₁₂H₁₆ON₄S·2HBr·½H₂O: C, 33.09; H, 4.51; N, 12.87; found: C, 33.18, 32.76; H, 4.82, 4.76; N, 12.75.

Vitamin B₁ is usually obtained from natural sources as the chloride hydrochloride. If desired, the bromide hydrobromide of the vitamin obtained by practicing the methods of either Example I or Example II may be converted into the chloride hydrochloride and the latter isolated in substantially pure form by the following procedure:

150 gms. of one of the condensation products obtained in Examples I and II are dissolved in 2250 cc. of hot methanol and shaken with silver chloride. It is best to use a 10% excess of the silver salt and to shake with several successive portions rather than to add all the silver salt at once. The reaction is over in one-half hour usually. The silver salts are allowed to settle out and are filtered off. The filtrate is treated with anhydrous ether whereby the chloride hydrochloride is precipitated out.

This synthetic chloride hydrochloride exhibits the same ultra violet absorption as does the chloride hydrochloride of the natural vitamin but has a lower melting point and is more soluble in alcoholic solvents. It can be crystallized in all the ways that are applicable to the natural vitamin salt if appropriate allowance is made for its greater solubilities. It will be referred to herein as the low melting chloride hydrochloride.

Pure crystals melting at 232-234° C. can be obtained by dissolving the crude chloride hydrochloride obtained as described above in methanol and precipitating it with ether, or by dissolving one gram of the crude product in one cc. of water, adding 9 cc. of boiling alcohol and allowing the vessel to stand in a freezing mixture to induce crystallization.

45 A sample of the pure natural vitamin salt extracted from rice polishings melted at 246° C. and a mixture of this with the above synthetic low melting chloride hydrochloride melted at 242-244° C. The synthetic low melting chloride hydrochloride, like the natural vitamin chloride hydrochloride, appears to hold about one-half molecule of water under the usual conditions. It has also been found to possess the same antineuritic 5 γ potency as is exhibited by the chloride hydrochloride of the natural vitamin.

Anal. calc. for C₁₂H₁₆ON₄S·2HCl·½H₂O: C, 41.60; H, 5.53; N, 16.8; found: C, 41.21, 41.30; H, 5.50, 5.48; N, 16.25, 16.26.

A method of obtaining the synthetic chloride hydrochloride from the bromide hydrobromide in a form having the same melting point as the vitamin chloride hydrochloride extracted from rice polishings is as follows:

150 gms. of the bromide hydrobromide condensation product obtained as described in Example I or Example II are dissolved in 300 cc. of water or 50% aqueous methanol and shaken with 225 gms. of silver chloride at room temperature for about three to four hours or until the reaction is completed. The silver bromide and chloride are filtered off and the filtrate is evaporated in vacuo to dryness.

It has been found that special treatment is necessary to make certain that the final product is quite free from silver. In order to accomplish

this, the residue above mentioned is dissolved in 1500 cc. of water and treated with a small amount of active charcoal (followed by filtration) until no further opalescence can be observed. The clear solution is evaporated in vacuo until incipient crystallization occurs, then treated with 10 volumes of hot, absolute alcohol. The resulting product is then filtered and dried. The product obtained by this method melts at about 246-250° C. according to the speed of heating.

It has been found that the low melting chloride hydrochloride and bromide hydrobromide produced by the methods hereinabove described can be converted into the high melting products by recrystallizing them from isopropyl alcohol or by dissolving them in absolute methyl alcohol and then precipitating with absolute ethyl alcohol.

Thus, two chloride hydrochlorides and bromide hydrobromides are obtained having the same antineuritic properties as those isolated from natural sources. One form of each salt has a melting point identical with that of the corresponding vitamin salt obtained from natural sources, while the other has a lower melting point. Either low or high melting salts can be obtained at will, by observing the directions above set forth.

It has been found that the antineuritic potency and ultra violet absorption of the bromide hydrobromide and those of the chloride hydrochloride are about the same, indicating that these properties do not depend upon the acid portions of the salt but upon the basic portion.

By coupling acid salts of pyrimethyl esters other than the above described bromide hydrobromide with a suitable thiazole, other salts of vitamin B₁ having comparable antineuritic properties may be prepared. The preparation of acid salts of a number of 2-methyl-6-amino-pyrimethyl esters and the coupling thereof with a thiazole nucleus to produce antineuritic compounds will now be described.

Example III

In accordance with this process, 2-methyl-6-amino-pyrimethyl-ethyl ether, obtained as described hereinbefore, is reacted with p-toluene sulphonic acid and the resulting p-toluene sulphonic acid salts of 2-methyl-6-amino-pyrimethyl-p-toluene sulphonate is condensed with 4-methyl-5-β-hydroxy-ethyl thiazole to produce a compound having the antineuritic activity characteristic of vitamin B₁. In practicing this process a mixture of 57 mgms. of 2-methyl-6-amino-pyrimethyl-ethyl ether and 125 mgms. of p-toluene sulphonic acid is heated at 110-120° C. for two hours. The mixture is then cooled, whereupon it solidifies. 50 mgms. of 4-methyl-5-β-hydroxy-ethyl thiazole are added and the resulting mixture is heated at 125° C. for forty-five minutes. The completely clear solution which is formed is cooled, and the product obtained is dissolved in 5 cc. of water. The pH is then adjusted to 5-6 by adding potassium bicarbonate, and the material is extracted with ether, the extracts being discarded. The aqueous solution obtained contains the p-toluene sulphonic acid salt of vitamin B₁ p-toluene sulphonate and exhibits an abundance of antineuritic activity.

Example IV

In this example benzene sulphonic acid is caused to react with 2-methyl-6-amino-pyri-

methyl-ethyl ether to produce the benzene sulphonic acid salt of 2-methyl-6-amino-pyrimethyl-benzene sulphonate. The latter compound is then caused to react with 4-methyl-5-β-hydroxyethyl thiazole to produce the benzene sulphonic acid salt of vitamin B₁ benzene sulphonate. In carrying out this process a mixture of 75.1 mgms. of benzene sulphonic acid with 26 mgms. of 2-methyl-6-amino-pyrimethyl-ethyl-ether is heated for two hours at 115° C. Then 22 mgms. of 4-methyl-5-β-hydroxy-ethyl thiazole are added and the mixture heated at 115° C. for one hour. The mixture is cooled, the product dissolved in 5 cc. of water, and potassium bicarbonate is added until the pH equals 5 or 6. Then the material is extracted with ether and the extracts discarded. The aqueous solution obtained possesses abundant antineuritic activity.

Example V

In practicing the process, a mixture of β-naphthalene sulphonic acid, 2-methyl-6-amino-pyrimethyl-ethyl ether and glacial acetic acid is heated and the resulting product is treated with 4-methyl-5-β-hydroxy-ethyl thiazole to produce the β-naphthalene sulphonic acid salt of vitamin B₁ β-naphthalene sulphonate. The specific details of practicing this process consist in preparing a mixture of 62.4 mgms. of β-naphthalene sulphonic acid, 16.7 mgms. of 2-methyl-6-amino-pyrimethyl-ethyl ether and 1 cc. of glacial acetic acid and heating it at 100° C. for two hours. The mixture is then cooled and evaporated to dryness in vacuo. To the crystalline product thus obtained 14.5 mgms. of 4-methyl-5-β-hydroxy-ethyl thiazole are added and the mixture is heated at 115° for one hour. The product after cooling is dissolved in 5 cc. of water, after which the pH is adjusted to equal 5-6 by adding potassium bicarbonate. The product is extracted with ether, the extracts being discarded, and the aqueous solution obtained exhibits abundant antineuritic activity.

Example VI

In this method, benzene sulphonic acid is heated with a 2-methyl-6-amino-pyrimethyl-ether and glacial acetic acid and the reaction product is condensed with 4-methyl-5-β-hydroxy-ethyl thiazole. The resulting product exhibits the characteristic antineuritic activity of salts of vitamin B₁. This method may be carried out by heating 64.7 mgms. of benzene sulphonic acid with 23 mgms. of 2-methyl-6-amino-pyrimethyl-ethyl ether in 1 cc. of glacial acetic acid for two hours at 116° C. This solution is evaporated to dryness in vacuo at 90° C. and a crystalline product results. Then 20 mgms. of 4-methyl-5-β-hydroxy-ethyl thiazole are added to the product and the mixture is heated at 115° C. for one hour. Upon cooling, the product is dissolved in 5 cc. of water and a pH equal 5-6 is obtained by adding potassium bicarbonate. The product is repeatedly extracted with ether and the extracts discarded. The aqueous solution obtained after extraction exhibits abundant antineuritic activity.

Antineuritic compounds similar to those described in Examples III, IV, V and VI may be obtained by substituting for the aryl sulphonic acids described therein suitable alkyl sulphonic acids, such as methyl sulphonic acid and its homologues. Persons skilled in the art may readily obtain the related alkyl sulphonates of the vitamin by suitably modifying the processes described

in these examples. The sulphonic acid esters employed comprise the formula:

wherein R is an alkyl or aryl radical of the type described herein.

Example VII

The hydrobromide of 2-methyl-6-amino-pyrimethyl-bromide produced in accordance with either Example I or Example II given hereinabove is caused to react with silver acetate to produce the corresponding acid ester, in which the bromide radical and hydrobromic acid of the pyrimethyl ester are replaced by the acetate radical and acetic acid, respectively. In carrying out this reaction 1.4 gms. of the hydrobromide of the substituted pyrimethyl-bromide are mixed with 1.8 gms. of silver acetate, 5 cc. of glacial acetic acid are added and the resulting mixture is heated on a steam bath for about one hour with occasional stirring. The reaction mixture is then cooled and filtered. The complete removal of the bromine atoms from the substituted pyrimidine is shown by the fact that the filtrate obtained gives no evidence of containing a halogen. The precipitate consisting of silver bromide is washed several times with small portions of glacial acetic acid and all of the filtrates are combined. A sufficient quantity of a 10% solution of hydrobromic acid in glacial acetic acid to replace the acetic acid, added to the amino group in the 6 position, by hydrobromic acid (1 molecular equivalent) is added to the filtrate and an excess of ether is added to precipitate the resulting compound. The precipitate which is the hydrobromide of 2-methyl-6-amino-pyrimethyl-acetate, is filtered out of the solution and the filtrate is washed with ether. The precipitate is then dissolved in butyl alcohol and an equivalent quantity of the hydrobromide of 4-methyl-5- β -hydroxy-ethyl thiazole is added to the solution which is then heated for one hour at about 115° C. The butyl alcohol is removed from the reaction product by evaporation and the residue is dissolved in water, filtered and its pH adjusted to 6. Physiological assays of this product show decided antineuritic activity.

It is preferable to couple the hydrobromide of the pyrimethyl-acetate with the thiazole because the salts of vitamin B₁ which have an acid reaction are the more stable ones and the presence of hydrobromic acid is therefore desirable in place of the relatively weak acetic acid in order to obtain a more stable antineuritic salt. However, it is not essential to employ the hydrobromide of this ester and antineuritic compounds may be obtained by using the acetic acid salt of the pyrimethyl-acetate in the coupling reaction.

Example VIII

By a reaction similar to that described under Example VII the lactic acid salt of 2-methyl-6-amino-pyrimethyl lactate may be employed to produce an acid salt of vitamin B₁ having antineuritic properties. In this process 1.7 gms. of 2-methyl-6-amino-pyrimethyl-bromide hydrobromide are caused to react with 1.07 gms. of silver lactate to produce the corresponding pyrimethyl lactate. This may be treated as described in Example VII with hydrobromic acid to replace

the lactic acid attached to the 6-amino group and then condensed with 4-methyl-5- β -hydroxy-ethyl thiazole. Or, the unsubstituted lactic acid salt of the pyrimethyl lactate may be condensed with the thiazole, if desired. The resulting products also exhibit the physiological properties of vitamin B₁.

Example IX

10 By procedure substantially identical with that described in Examples VII and VIII, 2-methyl-6-amino-pyrimethyl-bromide hydrobromide is treated with silver benzoate. The benzoate ion in the resulting product may be replaced by the bromide ion and the resulting product condensed with the hydrobromide of 4-methyl-5- β -hydroxy-ethyl thiazole. In this reaction, 1.4 gms. of the bromide hydrobromide of the substituted pyrimidine are caused to react with 2.29 gms. of silver benzoate, and in the remaining steps of the process sufficient quantities of hydrobromic acid and of 4-methyl-5- β -hydroxy-ethyl thiazole, respectively, are employed to constitute molar equivalents. Also the unplaced benzoic acid salt of the pyrimethyl benzoate may be utilized, if desired, in the coupling reaction. In either case, products having strong antineuritic action are obtained.

30 By methods analogous to the foregoing ones, the corresponding acid salts of the chloride, sulphate, phosphate and nitrate esters of the aforementioned pyrimethyl compound may be prepared and caused to condense with a suitable thiazole, for example, 4-methyl-5- β -hydroxy-ethyl thiazole, to produce compounds having antineuritic properties.

35 The antineuritic compounds described in the various examples given herein may be separated from their impurities and obtained in a substantially pure state by suitable adaptations of the method of isolation outlined in Example II hereof.

40 The fact that all of the compounds resulting from the coupling reactions described hereinabove exhibit antineuritic activity clearly demonstrated that this property is obtained in compounds having a substituted pyrimethyl group coupled with a substituted thiazole group and which possess the following general formula:

50 in which X represents an acid radical which may be varied almost at will. Although in all of the examples recited hereinabove, the pyrimethyl group has a methyl group located in the 2 position and an amino group in the 6 position and the thiazole group has a methyl group in the 4 position and a β -hydroxy-ethyl group in the 5 position, the invention is not limited to these particular derivatives. For example, the methyl

60 group in the 2 position of the pyrimethyl radical may be replaced by the homologues thereof, such as the ethyl and propyl groups. Likewise, the methyl group in the 4 position of the thiazole ring may be replaced by related groups, such as the ethyl and propyl radicals.

65 In the foregoing description pyrimethyl esters have been the reactive pyrimethyl compounds particularly described, but it is to be understood that the invention is not limited to the coupling with a thiazole of a pyrimethyl ester which has

been isolated as such before the coupling reaction is effected. The invention also contemplates the utilization of a pyrimethyl alcohol, ether or ester in the presence of an acid in a coupling reaction whereby the pyrimethyl group and the anion portion of the acid add directly to the nitrogen of the thiazole to produce a quaternary thiazole compound. These compounds are all examples of reactive pyrimethyl compounds as that term is employed herein.

In most of the above described coupling or condensing reactions, a basic thiazole, such as 4-methyl-5- β -hydroxy-ethyl thiazole, has been specifically mentioned. However, these reactions will also proceed satisfactorily if salts of the thiazole are employed instead of the free base. Thus, for example, the hydrobromide of 4-methyl-5- β -hydroxy-ethyl thiazole may be coupled with the hydrobromide of 2-methyl-6-amino-pyrimethyl-bromide to produce the hydrobromide of vitamin B₁. Hence, whenever the term "thiazole" is used in the annexed claims, it is intended to mean either the free base or a salt of the thiazole.

Also, in general, where 6-amino-pyrimethyl and other amino compounds are mentioned, the acid salts thereof formed by the addition of acids to the basic amino groups are also contemplated. Consequently, the formulae given herein and in the annexed claims for the basic amino compounds are intended to comprise the salts. For convenience of operation it is sometimes more advantageous to use the free base and at other times better to employ a salt thereof. The particular compound employed will of course be chosen to fit the requirements of the reaction involved.

Where alkyl groups are described as substituents in the various compounds mentioned herein, aralkyl groups may in general be used with satisfactory results. Hence, when the term "alkyl" is used herein and in the annexed claims, it is also intended to embrace the aralkyl groups.

What is claimed is:

1. The process which comprises reacting a 2-alkyl-6-amino-pyrimethyl ester with 4-methyl-5- β -hydroxy-ethyl-thiazole.

2. The process of producing antineuritic compounds which comprises reacting a 2-methyl-6-amino-pyrimethyl ester with 4-methyl-5- β -hydroxy-ethyl thiazole.

3. The process which comprises reacting 4-methyl-5- β -hydroxy-ethyl thiazole with a reactive 2-alkyl-6-amino-pyrimethyl compound which forms a quaternary antineuritic compound with the trivalent nitrogen atom of the thiazole.

4. The process of producing compound having antineuritic properties which comprises condensing 2-methyl-6-amino-pyrimethyl-acetate with 4-methyl-5- β -hydroxy-ethyl thiazole.

5. The process of producing compounds having antineuritic properties which comprises coupling a 2-methyl-6-amino-pyrimethyl ester, in which the acid radical or element is a member of the group consisting of the halogen, acetate, lactate, benzoate, nitrate, phosphate and sulphate radicals, with 4-methyl-5- β -hydroxy-ethyl thiazole.

6. The process which comprises treating a reactive pyrimethyl compound of the group consisting of 2-methyl-6-amino-pyrimethyl alcohol, ethers and esters with 4-methyl-5- β -hydroxy-ethyl thiazole in the presence of an acid.

7. The process of producing antineuritic com-

pounds which comprises reacting an ester of the group having the formulae

and

in which X is an acid radical and HX¹ is an acid, with 4-methyl-5- β -hydroxy-ethyl thiazole.

8. The process of producing antineuritic compounds which comprises reacting an ester of the group having the formulae

and

in which X and X¹ are selected from the group consisting of the halide, acetate, lactate, benzoate, nitrate, phosphate and sulphate radicles, with 4-methyl-5- β -hydroxy-ethyl thiazole.

9. An antineuritic compound of the group consisting of the compounds having the formulae:

and

10. An antineuritic compound of the group consisting of the compounds having the formulae:

and

11. The process which comprises treating in the presence of an acid a reactive pyrimethyl compound of the group consisting of a 2-methyl-6-amino-pyrimethyl alcohol, ether and ester with a thiazole having the formula

in which R is an alkyl group and Z is a member of the group consisting of OH and groups and elements readily convertible into OH.

12. The process which comprises reacting a substituted thiazole having the formula

in which R is an alkyl group and Z is a member of the group consisting of OH and groups and elements readily convertible into OH, with a reactive 2-alkyl-6-amino-pyrimethyl compound which forms a quaternary compound with the trivalent nitrogen atom of the thiazole.

13. The process which comprises reacting a substituted thiiazole having the formula

in which R is an alkyl group and Z is a member of the group consisting of OH and groups and elements readily convertible into OH, with a reactive 2-alkyl-6-amino-pyrimethyl ester.

14. The process which comprises treating a reactive pyrimethyl compound of the group consisting of 2-alkyl-6-amino-pyrimethyl alcohol, ethers and esters with 4-methyl-5- β -hydroxy-ethylthiazole in the presence of an acid.

15. The reaction product obtained by reacting a hydrobromide of 2-methyl-6-amino-pyrimethylbromide with 4-methyl-5- β -hydroxy-ethyl-thiazole, said product having the characteristic physiological properties of vitamin B₁.

16. A process for the preparation of vitamin B₁ hydrochloride which comprises converting β -ethoxy-propionic-ethyl ester to its corresponding sodioformyl derivative, condensing the latter with acetamidine to form 2-methyl-6-oxypyrimethyl-ethyl-ether, converting this last-named product into 2-methyl-6-halo-pyrimethyl-ethyl-ether, converting this into 2-methyl-6-amino-pyrimethyl-ethyl-ether, converting the latter product into 2-methyl-6-amino-pyrimethyl halide, and finally, condensing the latter product with 4-methyl-5- β -hydroxy-ethyl-thiazole - hydrochloride to form the desired salt of vitamin B₁.

17. A process for the preparation of vitamin B₁ bromide hydrobromide which comprises converting β -ethoxy-propionic-ethyl ester to its corresponding sodioformyl derivative, condensing the latter with acetamidine to form 2-methyl-6-oxy-pyrimethyl-ethyl-ether, converting this last-named product into 2-methyl-6-chlor-pyrimethyl-ethyl ether, converting this into 2-methyl-6-amino-pyrimethyl-ethyl-ether, converting the latter product into 2-methyl-6-amino-pyrimethyl-bromide, and, finally, condensing the latter product with 4-methyl-5- β -hydroxy-ethyl-thiazole-hydrobromide.

18. Process for the production of a substance having the physiological properties of vitamin B₁ which comprises condensing 2-methyl-6-amino-pyrimethyl-bromide with 4-methyl-5- β -hydroxy-ethyl thiazole.

19. An antineuritic compound of the structure:

having a melting point of 219° to 220° C.

10 20. The process for the production of an anti-
neuritic compound which comprises the conden-
sation of a hydrobromide of 2-methyl-6-amino-
pyrimethyl-bromide with 4-methyl-5- β -hydroxy-
ethyl thiazole in the presence of butanol at a
temperature of about 120° C.

15 temperature of about 120 °C.

21. The process for the production of an anti-
neuritic compound which comprises the conden-
sation of a hydrobromide of 2-methyl-6-amino-
pyrimethyl-bromide with 4-methyl-5- β -hydroxy-
20 ethyl thiazole in the presence of butanol.

20 22. The process of making antineuritic compounds which comprises condensing 4-methyl-5- β -hydroxy-ethyl thiazole with a compound having the formula

30 in which X and X' are acid radicals at least one of which is bromine and R is an alkyl group.

23. The process of making antineuritic compounds which comprises condensing 4-methyl-5- β -hydroxy-ethyl thiazole with a compound having the formula

in which X and X' are acid radicals at least one of which is bromine.

24. An antineuritic compound having the formula:

in which X and X' are acid radicals and at least one of which is bromine.

25. An antineuritic compound of the structure:

26. The process for converting a bromide hydrobromide compound such as is shown in claim 25 into its corresponding chloride hydrochloride which comprises reacting upon the former with silver chloride.

27. The process which comprises reacting upon 4-methyl-5- β -hydroxy-ethyl-thiazole with a 2-methyl-6-aminopyrimidyl-halide.

70 28. The process which comprises reacting upon a 4-alkyl-5- β -hydroxy-ethyl-thiazole with a reactive 6-amino-pyrimidyl-5-lower-alkyl ester.

75 29. The process which comprises reacting upon
a 4-alkyl-5- β -hydroxy-ethyl-thiazole with a 6-
amino-pyrimidyl-5-lower-alkyl-bromide.

30. The process which comprises reacting upon a 4-alkyl-5-hydroxy-alkyl-thiazole with a reactive 2-alkyl-6-amino-pyrimidyl-5-lower alkyl ester.

31. The process which comprises reacting upon a 4-alkyl-5-hydroxy-alkyl thiazole with a 2-alkyl-6-amino-pyrimidyl-5-lower alkyl halide.

32. The process which comprises reacting upon 4-methyl-5- β -hydroxyethyl-thiazole with a 2-lower alkyl-6-amino-pyrimethyl-halide.

33. The process which comprises reacting under acid conditions a reactive 2-lower-alkyl-6-amino-pyrimethyl ester with 4-methyl-5- β -hydroxy-ethyl thiazole.

34. The process which comprises reacting under acid conditions a reactive 2-methyl-6-amino-

pyrimethyl ester with 4-methyl-5- β -hydroxy-ethyl thiazole.

35. The process which comprises condensing a hydrobromide of 2-methyl-6-amino-pyrimethyl-bromide with 4-methyl-5- β -hydroxy-ethyl thiazole.

36. An antineuritic compound of the structure:

ROBERT R. WILLIAMS.
JOSEPH K. CLINE.
